UNITED STATES PATENT OFFICE.

JACOB M. SCHUNCK AND ANTON L. ZENDER, OF CELINA, OHIO.

MOVABLE-TOP WRITING-DESK.

SPECIFICATION forming part of Letters Patent No. 606,090, dated June 21, 1898.

Application filed November 26, 1897. Serial No. 659,794. (No model.)

To all whom it may concern:

Be it known that we, JACOB M. SCHUNCK and ANTON L. ZENDER, citizens of the United States, residing at Celina, county of Mercer, 5 and State of Ohio, have invented a new and useful Improvement in Desks having Mov- able Tops, of which the following is a speci- fication.

In the accompanying drawings, Figure 1 is 10 a perspective view of a desk with the im- proved movable top. Fig. 2 is a partial sec- tion of the same.

A denotes the movable top of the desk.

B B denote supporting antifriction-rollers. 15 These rollers have journals with bearings in the frame of the desk and in posts secured to said frame.

C C are rollers supported upon posts E and 20 adapted to rotate upon rails D when the top is moved.

D D indicate rails fixed to the top and 25 grooved underneath to rest upon and embrace the wheels or rollers B.

The rollers C serve to hold the top and its 30 rails D upon the rollers B, and by these de- vices the movement of the top is made smooth and certain and held in proper relation to the desk-body even though moved partly off from it, as indicated in Fig. 2.

E E denote the above-mentioned posts fixed 35 to the frame of the desk and extending up above the rails D.

Practically the entire upper part of the desk 40 can be uncovered and that by moving the top endwise and in either direction, and these movements can be effected without compelling the user of the desk to leave his seat.

It is preferred to make the whole top mov- 45 able, one advantage being that in any desk

provided with such top it can be ordinarily 40 moved in one direction without obstruction by an adjacent wall or other obstruction—as, for example, if it be situated in a corner of a room. The invention, however, comprises 45 a top supported as herein set forth and mov- able endwise, whether such top is adapted to cover the entire desk or not.

We are aware that desk-tops have been sup- 50 plied with rails and movable book-supporting platforms, and also that desk-tops have been 55 made movable toward their front, and such constructions are not herein claimed.

Having described our invention, we claim—

1. In combination with a desk, the top A, 55 the supporting-rollers B and means for hold- ing the top upon said rollers, said top being movable endwise in either direction to un- cover the desk, substantially as described.

2. In combination with a desk the top A, 60 the supporting-rollers B and means for hold- ing the top upon said rollers, comprising roll- ers C supported on the desk and bearing upon a part connected to the top, said top being movable endwise in either direction to un- 65 cover the desk substantially as described.

3. In combination with a desk, the top A, 70 the supporting-rollers B and means for hold- ing the top upon said rollers, comprising roll- ers C supported on the desk and bearing upon a part connected to the top, said part con- 75 sisting of rails D and said top being movable endwise in either direction to uncover the desk substantially as described.

JACOB M. SCHUNCK.
ANTON L. ZENDER.
